(57) **CLAIM**

The ornamental design for a MEDIA PLAYER, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a media player in accordance with our design;

FIG. 2 is a front view of the media player in accordance with our design;

FIG. 3 is a back view of the media player in accordance with our design;

FIG. 4 is a left side view of the media player in accordance with our design;

FIG. 5 is a right side view of the media player in accordance with our design;

FIG. 6 is a top view of the media player in accordance with our design; and

FIG. 7 is a bottom view of the media player in accordance with our design.

The bottom of the media player is flat and devoid of surface ornamentation. The color shown on the claimed design forms no part thereof. The broken lines shown on the claimed design form no part of the claimed design.
